CONTROL AND INDICATOR KNOB

Stuart G. Mundt, Syracuse, N. Y., assignor to Easy
Washing Machine Corporation, Syracuse, N. Y.,
a corporation of Delaware

Application September 18, 1952, Serial No. 31,513

Term of patent 14 years

(Cl. D26—1)

To all whom it may concern:

Be it known that I, Stuart G. Mundt, a citizen of the United States of America, residing at Syracuse, in the county of Onondaga and State of New York, have invented a new, original, and ornamental Design for a Control and Indicator Knob, of which the following is a specification, reference being had to the accompanying drawing, forming part thereof, in which:

Figure 1 is a front elevational view;
Figure 2 is a side elevational view;
Figure 3 is a rear elevational view;
Figure 4 is an axial sectional view taken substantially on the line 4—4 of Figure 1; and
Figure 5 is a fragmentary enlarged view showing the contour of the flutes.

I claim:

The ornamental design for a control and indicator knob, substantially as shown.

STUART G. MUNDT.
